Jacob Swedlin, New York, N. Y.

Application June 11, 1947, Serial No. 139,585

Term of patent 7 years

(Cl. D34—2)

To all whom it may concern:

Be it known that I, Jacob Swedlin, a citizen of the United States, residing at New York city, in the county of Kings and State of New York, have invented a new, original, and ornamental Design for a Stuffed Toy Animal or Similar Article, of which the following is a specification, reference being had to the accompanying drawing, forming a part thereof.

Fig. 1 is a front view of a stuffed toy animal or similar article, showing my new design.

Fig. 2 is a side view thereof.

Fig. 3 is a rear view thereof.

I claim:

The ornamental design for a stuffed toy animal or similar article, substantially as shown.

JACOB SWEDLIN.
